UNITED STATES PATENT OFFICE.

HENRY MANTHEY, OF LANSING, MICHIGAN, ASSIGNOR TO THE "NEW-WAY" MOTOR COMPANY, OF LANSING, MICHIGAN.

CHARGE-FORMING DEVICE FOR INTERNAL-COMBUSTION ENGINES.

1,28 380.

Specification of Letters Patent. Patented Dec. 10, 1918.

Original application filed June 10, 1916, Serial No. 102,915. Divided and this application filed April 17, 1917. Serial No. 162,643.

To all whom it may concern:

Be it known that I, HENRY MANTHEY, a citizen of the United States, residing at Lansing, in the county of Ingham and State of Michigan, have invented certain new and useful Improvements in Charge-Forming Devices for Internal-Combustion Engines, of which the following is a specification.

This invention relates to improvements in charge forming devices for internal combustion engines.

The main objects of this invention are:

First, to provide an improved charge forming device for internal combustion engines of very high efficiency.

Second, to provide an improved charge forming device for internal combustion engines which is adapted to the use of the heavier hydrocarbons such as kerosene and distillates.

Third, to provide an improved carburetor adapted for the use of such fuels in which a portion of the exhaust gases are used to heat and dilute the explosive charges for the engine.

Fourth, to provide an improved charge forming device for internal combustion engines which is simple and compact in structure and not likely to get out of repair in use.

Further objects and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a side view of my improved charge forming device partially in section through the fuel reservoir illustrating the means for controlling the fuel therein.

Fig. II is a detail vertical central section on a line corresponding to line 2—2 of Figs. III and IV, parts being shown in full lines for convenience in illustration.

Fig. III is a plan view of my improved carburetor.

Fig. IV is a detail horizontal section on a line corresponding to line 4—4 of Fig. I.

Fig. V is a detail vertical section on a line corresponding to line 5—5 of Fig. III showing details of the closure cap.

In the drawing, similar reference characters refer to similar parts throughout the several views and the sectional views are taken looking in the direction of the little arrows at the ends of the section lines.

This application is a continuation and division in part of my co-pending application, Serial No. 102,915, filed June 10, 1916.

Referring to the drawing, the body 1 of my improved carburetor is provided with a carbureting chamber 2, through which the exhaust pipe member 3 extends vertically.

The carbureting chamber is provided with a discharge 4 at one side connected to the manifold or engine conduit 6. The carburetor is controlled by the throttle 7 which, in practice, I preferably connect with a governor. The governor mechanism and connections are not shown as they form no part of my present invention.

The inlet passage 8 is arranged to deliver through the venturi restriction 9 against the side of the exhaust pipe member opposite the discharge 4. The inlet passage is provided with a slot-like mouth 10 disposed close to the section 11 of the exhaust pipe member so that the air passing thereto is more or less heated by coming in contact with or by the radiation from the exhaust pipe member. The exhaust pipe member is provided with a perforated cap 12 through which the gases are discharged.

While I preferably utilize the exhaust for heating the member 3 the same might be heated by hot water or otherwise.

An auxiliary air inlet 13 is provided and arranged to deliver to the carbureting chamber on the inlet side of the heating member so that this auxiliary air is delivered to the primary air and the fuel as it is discharged against the heating member. This auxiliary air inlet is controlled by a suction actuated valve 14 normally retained on its seat by the spring 15. The tension of this spring is adjusted by the nut 16 so that it may be adjusted to open under the desired suction.

The fuel nozzle 17 is disposed to deliver at the venturi 9 so that the fuel is discharged against the side of the heating member. This nozzle is controlled by the valve 18.

threaded for adjustment into the nozzle. A fuel passage 19 connects the nozzle to the reservoir 20.

The means for maintaining the constant 5 level of fuel in the reservoir 20 are described and claimed in my co-pending application referred to above and will not therefore be described in detail here. While I preferably employ the means for maintaining a constant 10 level in the reservoir 20 therein described other means may be employed.

I have discovered that overheating and the premature ignition and combustion of the explosive charge and consequent "hammering" 15 frequently accompanying the operation of motors of this type, in which the heavier hydrocarbons are employed as a fuel, can be overcome or eliminated by introducing a portion of the exhaust gases into the 20 explosive charge. The means which I have in this embodiment employed, to utilize this discovery comprises a pipe or conduit 40, one end of which is in communication with the exhaust 3 through the union 41, and 25 the other end of which is placed in communication with the discharge passage 4 through the union 42. By this means a portion of the hot exhaust gases is introduced into the charge and mixed therewith and then introduced 30 into the explosion chamber. The primary effect of the introduction of these exhaust gases into the charge and their mixture therewith is not thoroughly understood but the result of this introduction is apparently 35 to delay the combustion of the charge and thereby eliminate the "hammering" and also the overheating of engines employing the heavier hydrocarbons.

The cap 12 serves somewhat to restrict the 40 discharge of the gases, so that the portion of the exhaust gases introduced to the carburetor is introduced under force by the exhaust delivery from the engine. This delivery of the exhaust gases by force is a 45 feature of decided advantage in that it insures a further agitation and mixing of the carbureted mixture. The exhaust connection is preferably disposed at the rear of the venturi or mixing point for the primary 50 air and fuel and preferably delivers as shown in Fig. IV against the side of the exhaust member, where it passes through the carbureting chamber.

Having thus described my invention, what 55 I claim as new and desire to secure by Letters Patent is:

1. In a structure of the class described, the combination with an internal combustion engine, of a carbureter comprising a 60 carbureting chamber, an exhaust member extending through said chamber, there being a space entirely around said exhaust member open to a discharge for said chamber, said carbureting chamber having an air in-

let directed against the side of said exhaust 65 member opposite said discharge, said inlet being disposed so that the air passing thereto is heated by said exhaust member, said carbureting chamber being also provided with an auxiliary air inlet and having a suction air actuated inlet valve delivering at the rear of said primary air inlet on the inlet side of said exhaust member, a fuel nozzle disposed to coat with said primary air inlet, and a connection from said exhaust member to said carbureting chamber, whereby a portion of the exhaust gases are introduced to the explosive mixture.

2. In a structure of the class described, the combination with an internal combustion 80 engine, of a carbureter comprising a carbureting chamber, an exhaust member extending through said chamber, there being a space entirely around said exhaust member open to a discharge for said chamber, said carbureting chamber having an air inlet directed against the side of said exhaust member opposite said discharge, said inlet being disposed so that the air passing thereto is heated by said exhaust member, a fuel nozzle disposed to coat with said primary air inlet, and a connection from said exhaust member to said carbureting chamber, whereby a portion of the exhaust gases are introduced to the explosive mixture.

3. In a structure of the class described, the combination with an internal combustion engine, of a carbureter comprising a carbureting chamber, a heating member within said chamber connected to receive the exhaust gases, a primary air inlet passage and a fuel nozzle coating therewith directed against the said heating member, and an auxiliary air inlet having a suction actuated valve delivering on the inlet side of said heating member, and means for introducing a portion of the exhaust gases from said heating member to the carbureted mixture.

4. In a structure of the class described, the combination with an internal combustion 110 engine provided with an exhaust member, of a carbureter chamber, said exhaust member being disposed through said carbureting chamber so that the incoming air and fuel is heated thereby, and connections for said exhaust member to said carbureting chamber whereby a portion of the exhaust gases is introduced to and mixed with the charge 115 formed by said carbureter.

5. In a structure of the class described, 120 the combination of a carbureting chamber, an exhaust pipe member extending through said chamber, there being a space entirely around said member open to a discharge at one side, a primary air inlet passage 125 delivering to said carbureting chamber comprising a venturi directed against the side of said exhaust member opposite said dis-

charge, the inlet of said passage being disposed so that the air passing thereto is heated by said exhaust member, said carbureting chamber being also provided with 5 an auxiliary air inlet and having a suction actuated inlet valve delivering at the rear of said venturi on the inlet side of said exhaust pipe member, a fuel reservoir, and a fuel nozzle disposed in coacting relation 10 with said venturi.

6. In a structure of the class described, the combination of a carbureting chamber, an exhaust pipe member extending through said chamber, there being a space entirely 15 around said member open to a discharge at one side, a primary air inlet passage delivering to said carbureting chamber comprising a venturi directed against the side of said exhaust member opposite said discharge 20 charge, the inlet of said passage being disposed so that the air passing thereto is heated by said exhaust member, a fuel reservoir, and a fuel nozzle disposed in coacting relation with said venturi.

25 7. In a structure of the class described, the combination of a carbureting chamber, and exhaust pipe member extending through said chamber, there being a space entirely around said member open to a discharge at 30 one side, an air inlet passage delivering to said carbureting chamber comprising a venturi directed against the side of said exhaust member opposite said discharge, said carbureting chamber being also provided with an auxiliary air inlet and having 35 a suction actuated inlet valve, a fuel reservoir, and a fuel nozzle disposed in coacting 40 relation with said venturi.

8. In a structure of the class described, the combination of a carbureting chamber, an exhaust pipe member extending through said chamber, there being a space entirely 45 around said member open to a discharge at one side, an air inlet passage delivering to said carbureting chamber comprising a venturi directed against the side of said exhaust member opposite said discharge, a 50 fuel reservoir, and a fuel nozzle disposed in coacting relation with said venturi.

9. In a structure of the class described, the combination of a carbureting chamber, an exhaust pipe member extending vertically 55 through said chamber, there being a space entirely around said member open to a discharge at one side, an air inlet passage delivering to said carbureting chamber comprising a horizontally disposed venturi directed 60 against the side of said exhaust member opposite said discharge, a fuel reservoir,

and a fuel nozzle disposed horizontally in coacting relation with said venturi.

10. In a structure of the class described, the combination of a carbureting chamber, a 65 heating member extending within said chamber, there being a space around said member open to a discharge at one side, said carbureting chamber having a primary air inlet passage delivering against the said 70 heating member opposite said discharge, the inlet of said passage being disposed so that the air passing thereto is heated by said heating member, said carbureting chamber being also provided with an auxiliary air 75 inlet and having a suction actuated inlet valve, a fuel reservoir, and a fuel nozzle delivering with said primary air inlet against the said heating member.

11. In a structure of the class described; 80 the combination of a carbureting chamber, a heating member extending within said chamber, there being a space around said member open to a discharge at one side, said carbureting chamber having a primary air 85 inlet passage delivering against the said heating member opposite said discharge, said carbureting chamber being also provided with an auxiliary air inlet and having a suction actuated inlet valve, a fuel reservoir, and a fuel nozzle delivering with said 90 primary air against the said heating member.

12. In a structure of the class described, the combination of a carbureting chamber, a 95 heating member extending within said chamber, there being a space around said member open to a discharge at one side, said carbureting chamber having a primary air inlet passage delivering against the said 100 heating member opposite said discharge, the inlet of said passage being disposed so that the air passing thereto is heated by said heating member, a fuel reservoir, and a fuel nozzle delivering with said primary air 105 against the said heating member.

13. In a structure of the class described, the combination of a carbureting chamber, a heating member within said chamber, a primary air inlet passage and a fuel nozzle 110 coacting therewith directed against the said heating member, and an auxiliary air inlet having a suction actuated valve delivering on the inlet side of said heating member.

In witness whereof, I have hereunto set 115 my hand and seal in the presence of two witnesses.

HENRY MANTHEY. [L.S.]
